UNITED STATES PATENT OFFICE.

WILLIAM G. MAYER, OF PITTSBURGH, PENNSYLVANIA.

TRUCK HOIST.

1,418,387.

Specification of Letters Patent. Patented June 6, 1922.

Application filed February 25, 1921. Serial No. 447,736.

To all whom it may concern:

Be it known that I, WILLIAM G. MAYER, a citizen of the United States, residing at Pittsburgh, in the county of Allegheny and 5 State of Pennsylvania, have invented new and useful Improvements in Truck Hoists, of which the following is a specification.

This invention relates to dumping trucks, and more particularly to a hoist or lifting 10 means for elevating the front of the truck body for dumping the same.

One of the main objects of the invention is to provide an apparatus of simple construction and operation by means of which 15 comparatively great force may be applied to the front of the truck body for elevating the same. A further object is to provide an operating shaft in conjunction with a cable connected to the truck body and differential 20 means whereby the rate at which the cable is wound upon the shaft is reduced relative to the speed of rotation of said shaft thus materially increasing the force applied for lifting the truck body. Further objects will 25 appear from the detailed description.

In the drawings:

Figure 1 is a side view of the truck showing the hoist constructed in accordance with my invention as applied.

30 Figure 2 is a front view of the truck body and the hoist and associated parts.

Figure 3 is a detail, partly in section, of the means for steadyng the hoist when the truck body is in lowered position.

35 Figure 4 is a detail rear view of the head beam of the hoist.

Figure 5 is a diagrammatic view illustrating the relative positions of the sheaves when the truck body is fully raised.

40 Figure 6 is a similar view when the truck body is in lowered or normal position.

Truck A may be of any suitable or preferred type and includes a chassis B to which a sub-frame C is hinged at D to permit 45 raising of body 1 of the truck as illustrated in Figure 1. Bearing blocks 2 are secured by clips 3, or in any other suitable or preferred manner, to side sills 6 of chassis B. Each of these blocks is provided at its

50 forward end with two spaced ears 4 between which is pivotally secured the lower end of side arm 5 of boom 6. The upper ends of arms 5 are secured to the ends of blocks 7 provided at each end of a head beam 8, this

55 head beam being a casting and each of the blocks 7 being provided with a recess for

reception of a sheave 9 rotatably mounted in the block on a pin 10. The boom constructed and mounted in the manner described has free movement toward and away 60 from the front of body 1.

A channel bar 11 is secured to the front of the truck body centrally thereof and is provided at its lower end with a bracket 12 in which is mounted a sheave 13. A cable 65 14 is passed over sheaves 9 and beneath sheave 13, one end of this cable being wound on a drum 15 secured on an operating shaft 16 rotatably mounted in bearing blocks 12. This shaft is provided at each 70 end with a squared element 17 for reception of a crank handle for rotating the shaft in the known manner. The other end of cable 14 is wound upon a drum 18 of greater diameter than drum 15 secured on shaft 16 75 at the opposite side of channel bar 11 from drum 15, the drums being positioned equidistant from the channel bar.

When body 1 is in normal or lowered position, boom 6 is in substantially vertical position closely adjacent to the front of the body, as in Figure 2. When it is desired to raise the front of the body for dumping purposes, shaft 16 is rotated in such direction as to wind cable 14 onto drum 18 and off of drum 15, the cable being wound on these drums in opposite directions. Winding of the cable onto drum 18 exerts a lifting effect upon sheave 13 thus elevating the front of the body. As the weight of the 80 body as it is lifted is supported by cable 14 there will be a pull exerted on the cable which will tend to rotate shaft 16, through the medium of drum 15, in lifting direction; and as the cable is unwound from drum 15 85 as it is wound onto drum 18, a differential effect is obtained by means of which the rate at which the cable is wound onto drum 18 relative to the rate of rotation of shaft 16 is materially reduced thus increasing the 90 force applied to sheave 13 for raising the front of body 1; this renders it possible for the front of truck body 1 to be readily elevated for dumping purposes by a single operator and also eliminates all necessity of 95 providing the usual reducing gearing or other rather complicated mechanisms employed for this purpose. In addition the construction employed is direct acting and is composed of a minimum number of parts 100 of simple and durable construction. When 105 it is desired to lower the truck body the

operation above described is reversed. When in lowered position the truck body is locked by means of the cable 14 and drums 15 and 18 and the parts associated therewith, since 5 the end portions of the cable are wound upon these drums in opposite directions, as previously stated. To steady the boom 6 when body 1 is lowered, I provide a hook member 19 secured in the upper end of channel bar 10 11, this member being positioned to engage over the body 20 of head beam 8. As will be noted more clearly from Figure 3, blocks 7 at the ends of beam 8 project rearwardly an appreciable distance so as to follow the 15 front of the body during the hoisting operation, channel bar 11 passing between blocks 7. This provides a space between the blocks which is sufficient to accommodate sheave 13 thus permitting the front of body 1 to be 20 elevated to such an extent as to bring sheave 13 into horizontal alignment with sheaves 9, if desired or necessary. By this means it is possible to elevate the front of the body to a much greater extent than by 25 means of hoists of known type now commonly used.

By arranging the sheave 13 in alignment with channel bar 11, as in Figure 1, and providing the blocks 7 at the ends of the 30 head beam 8, it is possible to raise sheave 13 into substantial alignment with sheaves 9 as in Figure 5, thus permitting raising of the front of truck body 1 to a relatively great height. As will be understood, the cable 35 14 is of such length that when the truck body is thus raised it is wound onto the larger drum 18 and off of drum 15, the cable being wound off of drum 18 and onto drum

15 when the body is lowered, as in Figure 6.

While I have illustrated and described 40 herein the preferred construction of my invention it may be found desirable, in practice, to resort to changes in details of construction and arrangement of parts, and I intend to include all such variations, as fall 45 within the scope of the appended claims, in this application in which the preferred form only of my invention is disclosed.

What I claim is:—

1. In combination with a truck frame and a tiltably mounted body, a boom carried by the frame, an operating shaft rotatably mounted on the frame, two drums of different diameters secured on said shaft, sheaves carried by the boom, a sheave secured to the body below and between the boom sheaves, and a cable passed over the boom sheaves and under the body sheave, said cable being wound upon the drums in opposite directions. 60

2. In combination with a truck frame and a body hinged at its rearward end to said frame, a rotatably mounted shaft, drums of different diameters secured on said shaft, two sheaves mounted in advance of the body 65 and spaced apart transversely thereof, said sheaves being free from the body and held against vertical movement, a cable passed over the sheaves and having its ends secured to and wound upon the drums in opposite 70 directions and a member secured to the body and between the sheaves, the cable being passed beneath said member.

In testimony whereof I affix my signature.

WM. G. MAYER.
